US0D1080645S

(12) **United States Design Patent** (10) Patent No.: **US D1,080,645 S**
(45) Date of Patent: ** Jun. 24, 2025

(54) **DISPLAY SCREEN WITH GRAPHICAL USER INTERFACE**

(71) Applicant: **KABUSHIKI KAISHA TOYOTA JIDOSHOKKI**, Kariya (JP)

(72) Inventors: **Keisuke Akatsuka**, Kariya (JP); **Tadayuki Yakushi**, Kariya (JP); **Kouichi Sumigama**, Kariya (JP)

(73) Assignee: **KABUSHIKI KAISHA TOYOTA JIDOSHOKKI**, Kariya (JP)

(**) Term: **15 Years**

(21) Appl. No.: **29/861,682**

(22) Filed: **Dec. 1, 2022**

(30) **Foreign Application Priority Data**

Jun. 2, 2022 (JP) ..... 2022-011856 D
Jun. 2, 2022 (JP) ..... 2022-011857 D

(57) **CLAIM**

The ornamental design for a display screen with graphical user interface, as shown and described.

DESCRIPTION

The FIGURE is a front view of a display screen with graphical user interface showing our new design.

The claimed portions are enclosed by the dash-dotted lines, which denote the boundaries of the claimed design in the drawings and form no part of the claimed design.

1 Claim, 1 Drawing Sheet
